UNITED STATES PATENT OFFICE

FRANK R. HUNTER, OF KANSAS CITY, MISSOURI, ASSIGNEE, BY MESNE ASSIGNMENTS, TO WILSON-JONES COMPANY, OF CHICAGO, ILLINOIS, A CORPORATION OF MASSACHUSETTS

FUEL FEEDING SYSTEM

Application filed April 7, 1927. Serial No. 181,737.

This invention relates to fuel feeding systems, and particularly that type of system wherein the coal or other fuel is pulverized, mixed with air under pressure, conveyed to a mixing chamber, and nozzle, and then forced into the combustion chamber.

One of the objects of the instant invention, is to provide suitable means, interposed in the supply pipe of a fuel feeding system, which is especially adapted to remove fuel particles, of a predetermined size from the stream of fuel, and further adapted to simultaneously intermix primary air with the pulverized fuel to be burned.

Another object of the instant invention is to provide a fuel feeding system which has, in addition to the well known pulverizing mill, and means for introducing fuel thereto, novel devices for introducing the desired quantity of air to the pulverized fuel.

An even further object of this invention, is the provision of a fuel feeding system wherein a stream of air is conveyed under pressure. Another stream of air of the system being introduced at the proper point in the form of a draught, which is not forced into the mixing relation with the pulverized fuel, but is drawn into the air mixing chamber, by a whirling motion of the pulverized fuel and primary air.

Minor objects and specific details of construction of one form of the invention will appear during the course of the detailed specification referring to the accompanying drawings, wherein one embodiment of the invention is illustrated, and wherein:

Figures 1 and 2, make up a complete diagrammatical view of a fuel feeding system, made in accordance with this invention, the views for the most part being vertical central sections.

Fig. 3 is a perspective view of one embodiment of the expansion chamber, which is interposed in the supply pipe line.

Fig. 4 is an enlarged vertical cross-section of the supply pipe taken on line IV-IV of Fig. 2, looking in the direction of the arrow, and showing the end of the air mixing chamber.

Fig. 5 is a vertical longitudinal section, thru the combined secondary air mixing chamber, and nozzle, taken on line V-V of Fig. 4, and

Fig. 6 is a front end view of the mixing chamber nozzle.

Similar reference characters refer to like parts throughout the several views, and the numeral 7 designates an ordinary hopper, into which is dumped the coal to be pulverized and used in a fuel feeding system of this type. The hopper 7, empties into a horizontally disposed pipe 8, which houses a suitable worm feed 9, adapted to force coal from hopper 7, thru pipe 8 into a pulverizing mill 10, which is rotatably mounted on pipe 8. As is well known in the art, pulverizing mill 10 grinds and breaks the coal into dust before it is removed from the same to be conveyed to the fire box. The coal to be pulverized is forced thru pipe 8 into the mill 10, thru an opening 12, formed in the lower portion of the wall of pipe 8, just inside the mill 10. A partition 13 precludes movement of the coal beyond this opening 12. As the coal is passing from hopper 7 to opening 12, it is found highly desirable to intermingle the hot flue gases therewith. Accordingly, a conduit 14 communicates with pipe 8 between hopper 7 and mill 10. This conduit 14 preferably carries flue gases to the coal which are at a temperature very close to 450 degrees. Thus the coal passing thru pipe 8 to the mill is dried and heated, and since some of these flue gases at a high temperature pass into mill 10, it is obvious that during the pulverization, the coal is further dried and heated.

Any suitable fan 15, may be used to carry the pulverized fuel from mill 10 to the fire box; not here shown.

To produce the best results in the burning of pulverized fuel, it has been discovered that expansion chamber 16 should be used, which is interposed in the pipe line, leading from mill 10 to the fire box. As is shown in Fig. 1, pipe 8 has another opening 17, formed therein, thru which passes the pulverized fuel. Pipe 8, empties into the expansion chamber 16, and the sudden reduction of air pressure will cause separation of

the heavier parts of the pulverized fuel. To produce the best results, pipe 18, leading from expansion chamber is relatively greater in diameter than pipe 8 entering said chamber 16. Means should also be provided in the construction of the expansion chamber 16, which will permit of adjusting the amount of the fresh air which enters the same. One form of constructing a means for admitting the supply of air is shown here to be an upper and a lower aperture 19 and 20 respectively, each of which is provided with a slidably mounted cover 21, which may be adjusted to govern the size of the two apertures. The lower aperture 20 also serves as a clean out door for removing accumulations of coarse coal particles. When the pulverized fuel enters the expansion chamber 16, the heavier particles drop to the bottom; the lighter dust intermingles with the fresh air, and passes out the larger pipe 18a to the air mixing chamber and nozzle 22 and 23 respectively, which is here shown to be a single casting housing the exit end of pipe 18. A plurality of spirally arranged ribs 24 are formed on the inner surface of pipe 18a immediately adjacent the exit end thereof, which is housed in the air mixing chamber 22, as shown in Figs. 2 and 5. The air mixing chamber 22, is frusto-conical, and extends back from the exit end of pipe 18a where it is closed by a plate 25, having a series of openings 26 formed therethru and around pipe 18a. Plate 25 rotatably supports a disc 27 having openings 28 therein, which register with openings 26 when the draught to the air mixing chamber 22 is entirely open. Obviously, disc 27 may be rotated to partially close openings 26, and thereby provide an adjustable means for allowing a predetermined amount of air to enter mixing chamber 22. It is to be noticed that the air entering chamber 22 through the openings is not under pressure, but is in the form of a draught being pulled into the mixing chamber, and toward the stream of fuel by the whirling force of air and suspended pulverized fuel as it passes from the exit end of pipe 18a, ribs 24 having set up the whirling motion. As the pulverized fuel and primary air enter the air mixing chamber, the proper combustible mixture is formed, and the same passes thru the feed nozzle 23, having its major axis disposed in a horizontal plane. It has been found that the proper adjustment of the fresh air entering the expansion chamber 22, produces an exceptional fire. Combustion is practically perfect, and the efficiency of the fuel feeding system is extremely high.

Since it is not necessary to position the pulverized fuel conveying pipes in any particular relation with respect to the pulverizing mill and feeding nozzle, and the various novel parts of the fuel feeding system may

be altered as to construction and specific location, it is to be understood that the present invention is limited only by the scope of the appended claims.

What I claim as new and desire to be secured by Letters Patent is:

1. In a fuel feeding system the combination with a fuel pulverizing chamber and means for introducing fuel and flue gases thereinto, of means for conveying suspended fuel from said chamber comprising a conduit, an expansion chamber therein having inlets for introducing an air supply into said expansion chamber, a fan for drawing the fuel and air mixture from said expansion chamber, and an air mixing chamber and combustion nozzle connected to the fan to receive the discharge therefrom.

2. An apparatus for preparing and feeding fuel, comprising a pulverizing chamber, means for feeding a mixture of fuel and flue gas to said pulverizing chamber, a fan for exhausting a mixture of pulverized fuel and flue gas from said pulverizing chamber, a conduit connecting said fan and said pulverizing chamber, an expansion chamber in said conduit positioned intermediate said fan and said pulverizing chamber provided with inlets to admit air into said expansion chamber to mingle with the leaving mixture of pulverized fuel and flue gas, and an air mixing chamber connected to said fan to receive the discharge therefrom.

3. An apparatus for preparing and feeding fuel comprising a pulverizing chamber, a conduit extending through said chamber having inlet and outlet apertures and a partition in the conduit intermediate the apertures, means for feeding fuel and flue gas into the conduit towards the inlet thereof, an expansion chamber connected to said conduit external of said pulverizing chamber provided with inlets to admit air to said expansion chamber, a fan for exhausting a mixture of pulverized fuel, flue gas and air from said expansion chamber, and conduit means connecting said fan and said expansion chamber, said last named conduit means having a bore larger than said first conduit means and being positioned in alined longitudinal relation therewith.

In testimony whereof I hereunto affix my signature.

FRANK R. HUNTER.
